ATTY.

UNITED STATES PATENT OFFICE.

WILLIAM F. GUNN, OF PORTLAND, OREGON, ASSIGNEE OF ONE-SIXTH TO JAMES A. LONG, OF PORTLAND, OREGON.

GRINDING-MILL.

982,595.

Specification of Letters Patent. Patented Jan. 24, 1911.

Application filed February 17, 1908. Serial No. 416,379.

To all whom it may concern:

Be it known that I, WILLIAM F. GUNN, a citizen of the United States, and a resident of Portland, in the county of Multnomah and State of Oregon, have invented a new and useful Improvement in Grinding-Mills, of which the following is a specification, reference being had to the accompanying drawings as constituting a part thereof.

10 This invention has for its object to obtain a practical, durable and inexpensively constructed grinding mill, serviceable for grinding grains, coffee, spices, shells, and in fact any material of a similar nature to be reduced to a pulverized condition. To this end my mill is so arranged as to gradually reduce the material ground, in one operation or process of grinding, from a coarse state to as fine a state of comminution as desired; 15 and the grinding devices of my mill are provided with removable grinding faces, so that the grinding faces may be removed and substituted by others of a coarser or finer grade as desired.

20 Furthermore, my invention has for its object to provide a grinding mill so arranged as to facilitate the keeping of the same in good condition, and the making of repairs as required; my mill being so arranged as to 25 enable the removal and replacement of parts, or sections of parts as worn. And my mill embodies, besides, the several features hereinafter fully described and illustrated in the drawings above referred to.

30 In the drawings, Figure 1 is a longitudinal vertical section, taken approximately on a line indicated by the vertical arrow $x-x$ shown in Fig. 2, and looking in the direction pointed by the horizontal arrow; Fig. 40 2 is a transverse, vertical central section of my mill, as indicated by the arrow $x-x$ in Fig. 1; Fig. 3 is a cross section on a line $y-y$ of Fig. 1; and Fig. 4 is a cross section on a line pointed by arrow z in Fig. 1.

45 The letters designate the parts described.

My mill comprises a casing a , being a shell-like casting, made with a heavy base a' , provided with perforations b , b' , through which to insert screws, by which my mill is fastened to its table or support. The casing 50 is preferably made as shown by me in Fig. 1,

being divided through its vertical center into upper and lower sections a^2 , a^3 , fastened together by lug-screws c , c' . The upper casing-section a^2 is made with an inlet opening d , in which to insert a hopper e ; and the lower casing-section a^3 is made with a discharge opening f , in which is inserted a spout f' . The casing-section a^3 is made with integral lateral projections g , g , constituting the lower part of boxes, and to which are secured removable caps g' , constituting the upper parts of said boxes, and in which boxes, or journal bearings, is journaled the transverse shaft h , keyed in place. The caps g' are secured in place by screws g^5 , shown only in Fig. 1. The aperture g^2 in said journal bearings constitutes oil holes, and g^3 constitutes oil-wells. On the shaft h are rigidly mounted a balance wheel i , and a 65 pulley j , as shown in Fig. 2. The journal bearings for the shaft h are made of sufficiently larger circumference to insert babbitt k , as usual; and to restrain the shaft h against longitudinal movement, I make the 70 same with circumferential grooves l , into which a rib of the babbitt enters, as illustrated in Fig. 2.

Within the casing a there is rigidly mounted, on the shaft h , a cylinder m , the 75 circumferential face of which is made with perforations to receive screws m' , m' , by which to secure, on said circumferential face, grinding segments n , n' , each covering one-fourth of said circumferential face, and 80 the outer faces of which segments are made with corrugations of the degree of fineness suitable to the particular character of the work to be done. This construction enables me not only to replace such of the grinding 85 segments n , n' as may be injured or worn, but also to substitute for the same others of coarser or finer grade, as may be required for the work on hand. I prefer to make the 90 grinding-segments n , n' out of cast steel or 95 chilled cast-iron. The lower casing-section a^3 is made with registering lateral bosses o , having vertically elongated apertures o' , through which is inserted the shaft p of a hand set-wheel p' . On the shaft p is rigidly mounted an eccentric q .

Bearing against the under side of the cam

2
q and straddling such cam and the shaft p, is a box r, seated upon an adjustable coil-spring s. To provide for the adjustment of the tension of the coil-spring s, the lower 5 end thereof is seated on a nut-like collar s', vertically movable on a threaded post s², the box r having a central aperture r' in which the upper end of said vertical post s² telescopes, the function of said post being 10 only to support the collar s'. The cam q supports the lower end of a concave t, the upper end of which is hingedly supported by an adjustment tension device u. The latter comprises a bearing or box u adjustably 15 holding one end of a threaded rod u', bifurcated at its inner end so as to straddle the hinge-lug t' of said concave t, and the parts being united by a pin u². On the rod u' is 20 a movable nut-like collar u³, against which bears one end of the coil-spring u⁴, and by which collar the tension of said coil-spring u⁴ is adjusted. The outer end of the rod u' is also threaded and thereon is placed a hand 25 set-wheel u⁵. Thus, by the adjustment of such hand set-wheel u⁵, the rod u' may be lengthened and shortened and thereby the space between the opposed grinding faces of the cylinder m and the concave t may be increased and diminished as required.

30 To the interior concaved or grinding face of the concave t are removably affixed, by screws v, concaved shoe-segments t², the outer or grinding faces of which are suitably corrugated, coarse or fine as required, to co- 35 operate with the grinding-segments n, n' of the cylinder m. The concave is reinforced at t⁵ to provide a stronger bearing for the screws v, and has a web t⁶ extending along the back. Different sets of grinding faces, 40 coarse and fine, should also be provided for the concave t, from which to make a selection and adapt my mill to the particular grade of work on hand.

To keep the material being ground from 45 passing out through the side spaces, between the opposed grinding faces, the concave t is made with integral side-flanges t³, arranged to inclose the lateral faces of the grinding-segments n, n', on the periphery of the cylinder m. At the upper end of the concave t said flanges t³ widen into flanges t⁴, so as to 50 inclose the discharge-end or spout of the hopper e, as more readily seen in Fig. 1. To keep the grinding faces of the segments n, n' 55 affixed to the cylinder m clean, I provide a brush w, fastened to a plate w', and adjustably supported by set-screws w² of brackets w³, fastened to the inner sides of the case a. This feature is more particularly shown in 60 Fig. 4.

Since the concave t is held against the cylinder m by the coil-springs u⁴ and s, should any hard, coarse object get into the material being ground, no injury would result to the

grinding faces, but the latter would be 65 merely forced farther apart for the time, to allow such hard substance to pass through. The bearing of the grinding faces is adjusted by the set-wheels p', u⁵.

To remove the concave, for the purpose of 70 renewing or replacing its grinding segments, it is only necessary to release the spring s and remove the pin u², through a hole a⁴. An opening a⁵ is also provided to facilitate the adjustment of the nut-collar u³. 75

Though I have described the peripheral grinding face of my mill as made of segments, and this is no doubt the more practical way of making the same, I am not to be understood as limiting myself to such construction. A one-piece ring-like grinding face could be removably fastened to the periphery of my cylinder, and this feature is an unimportant element in the other combinations of my mill. 80

85 I claim:

1. In a grinding mill, the combination of a case, a cylinder rotatably mounted therein, a concave, a threaded post, a box supported on the upper end of said post, said box 90 having slotted sides, a collar on the lower end of the post, a coil-spring seated on said collar and bearing against the box, a shaft journaled in the case and extending through the slotted sides of the box, a cam fast on 95 said shaft within said box, said cam bearing against the under face of the lower end of the concave, and spring-controlled means whereby to adjust the upper end of said concave toward and from the rotating cylinder. 100

2. In a grinding mill, the combination of a case, a cylinder rotatably mounted therein, a concave, a spring-seated vertically adjustable box, a shaft journaled in the case and extending through slots therefor provided in 105 said box, a cam rigid on said shaft within said box and bearing against the under side of the lower end of said concave, a bearing in the upper end of the case, a rod, threaded at its extremities, supported in said bearing, 110 the inner end of which rod is pivotally connected to the upper end of the concave, a nut on the outer threaded extremity of said rod, a collar on the inner threaded extremity of said rod, and a coil-spring bearing 115 against said collar.

3. In a grinding mill, the combination of a case, a cylinder rotatably mounted therein, a concave, a threaded post, a box supported on the upper end of said post, said box having slotted sides, a collar on the lower end of the post, a coil-spring seated on said collar and bearing against the box, a shaft journaled in the case and extending through the slotted sides of the box, a cam fast on said 120 shaft within said box, said cam bearing against the under face of the lower end of the concave, a bearing in the upper end of 125

the case, a rod, threaded at its extremities, supported in said bearing, the inner end of which rod is pivotally connected to the upper end of the concave, a nut on the outer 5 threaded extremity of said rod, a nut-like collar on the inner threaded extremity of said rod, and a coil-spring bearing against said collar, and having its tension adjusted by the latter.

WILLIAM F. GUNN.
